Application June 25, 1958, Serial No. 51,539

Term of patent 14 years

(Cl. D26—13)

Fig. 1.

Fig. 2.

Fig. 4.

Fig. 3.

Fig. 1 is a front elevational view of a weatherproof wall plate for a press switch or similar article, showing my new design;

Fig. 2 is a side elevational view, the opposite side having substantially the same appearance;

Fig. 3 is an end elevational view, the opposite end having substantially the same appearance, and

Fig. 4 is a fragmentary cross-sectional view thereof, taken substantially on line 4-4 in Fig. 1.

The dominant features of my new design are shown in solid lines in the drawing.

I claim:

The ornamental design for a weatherproof wall plate for a press switch or similar article, substantially as shown and described.
